UNITED STATES PATENT OFFICE.

HENRY S. MCKEE, OF PITTSBURG, PENNSYLVANIA.

DESIGN FOR A BREAD-PLATE.

Specification forming part of Design No. 6,636, dated May 6, 1873; application filed April 17, 1873.

To all whom it may concern:

Be it known that I, HENRY S. MCKEE, of Pittsburgh, in the county of Allegheny and in the State of Pennsylvania, have invented a certain new and useful Design for Bread-Plate; and do hereby declare that the following is a full, clear, and exact description thereof, reference being had to the accompanying drawing and to the letters of reference marked thereon making a part of this specification.

The nature of my design is fully represented in the accompanying drawing, to which reference is made.

A represents a bread-plate of any desired form or shape, in the center of which is stamped or otherwise affixed a representation of a sheaf of wheat, marked B in the drawing. One of

the rims on one side of the plate has the words "Give us this day," and the rim on the opposite side has the words "our daily bread."

The bread-plate and the design upon the same may be made of silver, glass, china, or any other suitable material, and in one or more colors, and otherwise ornamented in any desired manner.

What I claim as my invention is—

The design for bread-plate, as herein shown and described.

In testimony that I claim the foregoing I have hereunto set my hand this 21st day of February, 1873.

HENRY S. MCKEE.
